UNITED STATES PATENT OFFICE.

LEE L. STRASBURGER AND GEORGE W. GOODE, OF ATLANTA, GEORGIA.

BOTTLE-FILLING MACHINE.

Application filed September 12, 1921. Serial No. 500,069.

To all whom it may concern:

Be it known that we, LEE L. STRASBURGER and GEORGE W. GOODE, citizens of the United States, residing at Atlanta, in the county of Fulton and State of Georgia, have invented 5 certain new and useful Improvements in Bottle-Filling Machines, of which the following is a specification, reference being had thereto to the accompanying drawing.

10 The present invention relates to filling machines operating on the principle of the siphon. In the operation of machines of this character liquid is conveyed to a plurality of bottles, or other receptacles, by a series of siphon tubes, the flow of liquid being automatically started when the siphon tubes are inserted in the bottles, or other receptacles, and ceasing when the level of the liquid in the bottle or receptacle reaches the 15 level of the liquid in the reservoir. Bottle-filling machines of this general type are well known, and the object of the present invention is to effect certain improvements which will be fully described hereinafter and then 20 particularly claimed.

25 Referring to the accompanying drawings, which illustrate a filling machine embodying our improvements,

Fig. 1 is a front elevation of the machine; 30 Fig. 2, is a side elevation thereof; Fig. 3 is a fragmentary vertical section through the reservoir, or tank, showing the float mechanism for automatically maintaining the level of the liquid substantially 35 constant;

Fig. 4 is a perspective view of the stand, or frame, which supports the tank, and illustrates the bottle-holding shelf and connections for operating the same;

40 Fig. 5 is a detail view illustrating the universal supports in which the siphon tubes are hung; and

Fig. 6 is a view of the siphon-tube nozzle, showing in section the slidable sleeve valve 45 and the union between the nozzle and siphon tube.

The machine comprises a tank, or reservoir, 1, rigidly supported on a stand 2. The stand is preferably of metallic tubular construction and of the form clearly illustrated 50 in Fig. 4, although it may be constructed of wood and have any other suitable form, without departing from our invention. The tank is preferably constructed of glass or 55 rubber, having all joints filled with pliable

rubber to make it liquid-tight and non-corroding.

Liquid is admitted into the tank through the connections and float valve illustrated by Fig. 3. Numeral 3 in this view designates a pipe, or hose, communicating with the source of liquid supply. Numeral 4 designates screw-threaded fitting which passes through an aperture in the tank and screws into pipe 3, a nut 5 and washer 6 being provided to effect a tight joint. Fitting 4 passes through a central hole in a bar 8, and the lower end of said fitting has an integral flange 7 which is clamped against the under surface of bar 8 when nut 5 is tightened. A 60 float 9, of cork or other suitable material, has a transverse slot adjacent its upper end, and the slotted ends of a pair of arms 10 are slidably and pivotally supported on a pin passing through said slot and fixed to 65 the float. The outer ends of arms 10 are pivoted between depending ears formed on the outer ends of bar 8. The float is thus constrained to move vertically under variations of liquid level in the tank. The upper 70 end of the float is tapered to fit the tapered opening in the lower end of fitting 4, thereby acting as a valve to admit and stop the flow of liquid into the tank, and automatically maintaining the level of liquid 75 substantially constant.

The siphon tubes through which liquid is conveyed from the tank to the bottles, or other receptacles, to be filled are hung in universal supports mounted on a bar 11, 80 which is attached to the ends of brackets 12 projecting upwardly and forwardly from the sides of the tank. The tubes comprise flexible portions 13 attached at their lower 85 ends to short pipes which communicate with the interior of the tank adjacent the bottom thereof and attached at their upper ends to elbow pipes 14. The latter pass through apertures in discs 15, which are pivoted to the depending heads of bolts 16. Bolts 16 90 are swivelled in rod 11, and are provided with threaded upper ends on which are screwed nuts 17. This construction provides a simple and efficient universal support for the siphon tubes, facilitating their 95 manipulation and permitting them to be readily disconnected from bar 11 whenever it becomes necessary to refill the tubes to start the siphoning action. The outer ends of elbow pipes 14 are connected by means 100 110

of unions 15' with nozzles 16', each of which has a head 17 and an orifice 18 adjacent the head. A sleeve 19, sliding on the nozzle, is adapted to cover the orifice normally and thereby prevent the flow of liquid, but when a nozzle is inserted in a bottle and the bottle raised, a flange 19' on the upper end of the sleeve engages with the bottle top and the sleeve is moved upwardly until said flange comes into engagement with the union, thereby uncovering the orifice and permitting the flow of liquid until the level of liquid in the bottle reaches the level of liquid in the tank, whereupon the flow ceases.

15 As plainly shown in Fig. 6, the nozzle 16 has a reduced upper portion which forms at its junction with the enlarged lower portion an annular shoulder which is adapted to contact with the inwardly projecting annular flange of sleeve 19. The nozzle has a second annular shoulder at the point of junction between the enlarged portion and head 17, and the parts are so proportioned that the sleeve 19 will just rest on this second shoulder when said sleeve is at its lowest position, the sleeve being stopped in its downward movement by the engagement of its inwardly projecting flange with the upper annular shoulder of the nozzle. This construction eliminates wear on the lower end of the sleeve and prevents the sleeve from striking and injuring the head 17.

A shelf 20 is located at the front of the machine directly under the siphon tubes and functions to support the bottles and bring them into correct position for filling. This shelf has a marginal vertical flange which is continuous except for a gap at one end of the shelf, whereby the bottles are properly maintained on the shelf and any liquid overflow is directed to a definite point where it may be caught in a suitable receptacle. The shelf has attached to the bottom thereof a pair of rearwardly extending arms 21 which are rigidly secured to a shaft 22 journalled in the side bars 23 of the stand. The rear end of each arm 21 is connected to the upper end of a coil spring 24, the lower end of which is attached to the side bar 25 of the stand. The shelf is therefore biased to move upwardly by the springs. For moving the shelf down against the tension of the springs, there is provided a treadle bar 26, having its rear end universally pivoted in a bracket 27 attached to a frame bar 28 and terminating at its front end in a treadle 29. A bar 30 is pivoted at its lower end to treadle bar 26 and is pivoted at its upper end to a bar 30'. The front end of bar 30' is fixed to the underside of the table while the rear end thereof is journalled on shaft 22. For guiding the treadle bar 26 and holding it in a plurality of positions, there is provided a pair of spaced brackets 31 and 32, which depend from the longitudinal frame bar 33, the

treadle bar projecting through the slot formed by opposing edges of the brackets and being thereby guided in its vertical movements. A plurality of teeth are formed on the edge of bracket 32, whereby when the treadle has been operated to the desired position it may be held in such position by moving it laterally into the space between adjacent teeth. As an auxiliary means for holding the shelf against downward movement, we provide a resilient strip 34 fixed centrally to the inner edge of the shelf with its free ends adapted to engage ratchet teeth 35 which are formed on or attached to the vertical frame bars 36. To permit the table to be lowered springs 34 are retracted manually from the ratchet teeth.

The operation of the machine may be briefly described as follows. Assuming the shelf 20 in lower position and held in such position by engagement of the treadle bar with the lower teeth on bracket 32, the operator places a number of empty bottles on the shelf and manually directs a siphon nozzle into the mouth of each bottle. He then disengages the treadle from the bracket teeth and permits the springs 24 to move the shelf upward to the required position, whereupon he engages the treadle bar with the bracket teeth in order to hold the shelf in such position. The bottles upon being raised with the shelf engage the flanges of sleeve valves 19, raising said sleeve valves until stopped by engagement thereof with unions 15'. The raising of the sleeve valves uncovers orifices 18 and causes the liquid to flow into the bottles until the latter are filled, whereupon the flow of liquid automatically ceases. It is to be particularly noted that it is the engagement of sleeve valves 19 with unions 15' which determines the height to which the shelf is to be raised in order to effect complete filling of the bottles or other receptacles; the lower the bottle, the higher the shelf; and, conversely, the higher the bottle the lower the shelf. Our machine is particularly adapted for filling bottles of different heights, since it has means for holding the shelf at a plurality of elevations and means for automatically determining the elevation required for a particular height of bottle.

It is not necessary to operate the shelf while filling bottles of the same height, since the flexible mounting of the siphon tubes permits the filled bottles to be withdrawn very readily from the nozzles and the substitution therefor of empty bottles. When, however, it is desired to fill bottles of a different height the operator manually disengages the ends of spring strip 34 from ratchet teeth 35 and treadle bar 26 from the rack teeth, whereupon the shelf is lowered, the filled bottles removed and empty bottles of a different height placed on the shelf.

The shelf is then permitted to rise under tension of the springs until the flanges of nozzles 19 come into engagement with unions 15, thus automatically determining the proper elevation of the table for the particular height of bottle.

It might happen, particularly in filling extra large bottles, that the shelf would become so heavily loaded as to overcome the tension of springs 24. Under this condition, if the treadle bar should be accidentally disengaged from its holding rack, the shelf with its load of bottles would fall with consequent breakage. It is to eliminate the possibility of an accident of this sort that we provide the holding means consisting of flexible strip 34 and coacting ratchet teeth 35.

Having particularly described a machine embodying our improvements, what we claim as new and desire to secure by Letters Patent is:—

1. A filling machine comprising a stand, a tank supported thereon, a plurality of siphon tubes communicating with said tank and supported forwardly thereof, a shelf pivoted on said stand and normally biased to move upwardly beneath said tubes, a treadle connected with said shelf, a rack on said stand for holding said treadle in a plurality of positions, and a ratchet for preventing downward movement of the shelf.

2. A filling machine comprising a stand, a tank supported thereon, a plurality of siphon tubes communicating with said tank, a shelf pivoted on said stand and biased to move upwardly beneath said tubes, a treadle connected with said shelf, a rack on said stand for holding said treadle in a plurality of positions, a spring strip secured centrally to the inner edge of said shelf and ratchet teeth on said stand adapted to be engaged by the free ends of said strip.

3. A filling machine comprising a stand, a tank supported thereon, a rod supported above and forwardly of said tank, a plural-

ity of siphon tubes communicating with said tank and universally supported at spaced intervals on said rod, a horizontal shelf pivotally supported on said stand and extending beneath said tubes, spring means tending to move said shelf upwardly, a treadle connected with said shelf, and a rack on said stand adapted to be engaged by said treadle.

4. In a bottle-filling machine, a tank, a siphon tube communicating therewith, a support extending forwardly of said tank, a bolt swivelled in said support having an upper threaded end and a nut thereon, an apertured member pivoted to the lower end of said bolt, said siphon tube having an elbow passing loosely through the aperture of said member.

5. In a bottle filling machine, a tank, a siphon tube communicating therewith, said tube including an elbow, a support extending forwardly of said tank, a bolt swivelled in said support having an upper threaded end and a nut thereon, a member pivoted to the lower end of said bolt and loosely engaging the elbow of said tube.

6. In a bottle filling machine, a tank, a siphon tube communicating therewith and supported forwardly thereof, said tube including an elbow, a nozzle and a union connecting said elbow and nozzle, said nozzle comprising a head, a lower portion of smaller diameter than the head and an upper portion of smaller diameter than said lower portion, said nozzle having a lateral opening adjacent its head, and a sleeve slideable on said nozzle and normally covering the orifice thereof, said sleeve having an inwardly projecting annular flange adapted to contact in its lower position the annular shoulder formed at the junction of said upper and lower portions.

In testimony whereof we hereunto affix our signatures.

LEE L. STRASBURGER.
GEORGE W. GOODE.
